UNITED STATES PATENT OFFICE.

IRA O. MILLER, OF TOPEKA, KANSAS.

DESIGN FOR A STOVE-LID AND PAN LIFTER.

SPECIFICATION forming part of Design No. 28,940, dated June 28, 1898.

Application filed May 28, 1898. Serial No. 682,070. Term of patent 3½ years.

All whom it may concern:
It is known that I, IRA O. MILLER, residing at Topeka, in the county of Shawnee and State of Kansas, have invented and produced a new useful Design for a Stove-Lid and Pan Lifter, of which the following is a specification:

his invention is a new and useful design of a stove-lid and pan lifter, the essential feature of the design being the cylindrical shape of the shank or central portion and the similarly curved prongs at each end of the shank.

the invention consists, further, in certain other features of design hereinafter fully described.

the drawings forming a part of this specification, Figure 1 is a perspective view of a stove-lid and pan lifter constructed in accordance with my design. Fig. 2 is a side or edge view of the same. Fig. 3 is an edge view.

Referring now to the drawings, A indicates a cylindrical-shaped shank or body portion, B a curved prong at one end, C an ab-

ruptly curved prong, and D a longitudinally projecting prong. The face of the prong end is flattened, as shown at E.

F indicates a prong at the opposite end of the shank or body portion, and G a prong projecting in the direction of the prong F, and H a short prong projecting at an angle to both the prongs F and G.

I indicates the flattened face of the prong end, and K an orifice or opening produced in the said end.

A stove-lid or pan lifter constructed in accordance with this design is ornamental and also useful, the operation thereof being obvious to any one skilled in the art to which it relates.

Having thus fully described my invention, what I claim as new, and desire to secure by Letters Patent of the United States, is—

The design for a stove-lid and pan lifter, substantially as herein shown and described.

IRA O. MILLER.
